UNITED STATES PATENT OFFICE.

CLARK M. COLE, OF ERIE, PENNSYLVANIA.

ICE-CREEPER.

1,102,646.

Specification of Letters Patent.

Patented July 7, 1914.

Application filed February 4, 1913. Serial No. 746,131.

To all whom it may concern:

Be it known that I, CLARK M. COLE, a citizen of the United States, residing at Erie, in the county of Erie and State of Pennsylvania, have invented new and useful Improvements in Ice-Creepers, of which the following is a specification.

This invention relates to ice creepers and consists in certain improvements in the construction thereof as will be hereinafter fully described and pointed out in the claim.

The object of the invention is to form an ice creeper adapted to be secured to the heel of the shoe, so that it may be readily attached and detached to the heels and readily fit to different sizes of heels.

The invention is illustrated in the accompanying drawings as follows:—

Figure 1 shows a plan view of the device with the parts in open position. Fig. 2 is a similar view with the parts in closed position. Fig. 3 is a front view of the creeper. Fig. 4 is a section on the line 4—4 in Fig. 1. Fig. 5 is a section on the line 5—5 in Fig. 1.

The creeper has the base plate 1 which is preferably of a shape to extend around the margin of the heel. Spurs 2 are formed on the bottom of the base plate 1. As shown they are riveted to the base plate. The base plate has the front portions 3 which are separated at 4 to permit the ends to be forced toward and from each other and fastens the plate to and unfastens it from the heel. The side and front plates 5 extend upwardly from the bottom plate 1. A notch 6 is cut in the rear of the bottom plate so that the flexibility of the plate 5 at 7 will permit of the movement of the side pieces sufficiently to clamp them to a heel and to permit their removal.

A clamping bar 8 has a hook or projection 9 at one end. The opposite end of the bar has the reduced portion 10 which extends through a perforation at the front of the side 5. The end of the bar extends be-

tween the ears 11 on a cam lever 12 and is pivotally secured therein by a pin 13. The front face has a series of perforations 15 through one of which the hook 9 extends. By means of this hook and these different perforations the creeper may be fitted to the heel of a wearer. When fitted the hook 9 is turned down at 14 so as to maintain the bar permanently in place.

In operation the device is fitted to the heel as just hereinbefore described. The creeper is placed on the heel in the open position shown in Fig. 1 and then the lever 12 is swung to the position shown in Fig. 2 thus drawing the ends 3 toward each other and clamping the sides 5 against the sides of the heel. In order to make a more secure engagement between the sides and the heel I prefer to form the shoulders 16 in the sides which under the pressure of the clamp are forced into the material of the heel so as to assure the engagement of the creeper as it is worn. This shoulder can be preferably formed by bending in the sides 5 as shown in section in Fig. 4.

What I claim as new is:—

In an ice creeper, the combination of a base plate having an opening therein at the front and at the rear and having downwardly extending spurs and flanges of resilient metal extending upwardly therefrom and forming a flexible portion at the rear opening of the base plate through the resilient quality of the upwardly extending flange; and means at the front of the creeper for drawing the front ends of the plates toward each other to clamp the side flanges on a heel.

In testimony whereof I have hereunto set my hand in the presence of two subscribing witnesses.

CLARK M. COLE.
